UNITED STATES PATENT OFFICE

FRANK J. PAIK, OF RIVERSIDE, ILLINOIS, ASSIGNOR TO EMIL J. PAIDAR COMPANY, OF CHICAGO, ILLINOIS, A CORPORATION OF ILLINOIS

DESIGN FOR A CABINET OR SIMILAR ARTICLE

Application filed July 26, 1929. Serial No. 32,222. Term of patent 7 years.

To all whom it may concern:

Be it known that I, FRANK J. PAIK, a citizen of the United States, and a resident of the village of Riverside, in the county of Cook and State of Illinois, have invented a new, original, and ornamental Design for a Cabinet or Similar Article, of which the following is the specification, reference being had to the accompanying drawing, forming a part hereof.

In the drawing:

I claim:

The ornamental design for a cabinet or similar article, as shown.

FRANK J. PAIK.
